CLAIM

The ornamental design for a tire as shown and described.

DESCRIPTION

FIG. 1 is a perspective view of a first embodiment of a tire of our new design, it being understood that the tread is repeated throughout the circumference of the tire;

FIG. 2 is a front view;

FIG. 3 is a right side view;

FIG. 4 is a section view taken along line 4 of FIG. 2;

FIG. 5 is a perspective view of a second embodiment of a tire of our new design, it being understood that the tread is repeated throughout the circumference of the tire;

FIG. 6 is a front view of the embodiment of FIG. 5;

FIG. 7 is a right side view of the embodiment of FIG. 5;

FIG. 8 is a section view taken along line 8 of FIG. 6; and, FIG. 9 is an enlarged view of a portion of the tread of the embodiment of FIG. 6.

The dashed lines in the drawings show environmental features of the tire and form no part of the following claim.
